Primary Examiner — Kevin K Rudzinski*Assistant Examiner* — Richard Kearney(74) *Attorney, Agent, or Firm* — Middleton Reutlinger(57) **CLAIM**

The ornamental designs for a zipper pull, as shown and described.

DESCRIPTION

FIG. 1 is a first perspective view of a zipper pull design; FIG. 2 is a second perspective view of the zipper pull design of FIG. 1;

FIG. 3 is a front view of the zipper pull design of FIG. 1; FIG. 4 is a side view of the zipper pull design of FIG. 1; FIG. 5 is a top view of the zipper pull design of FIG. 1; and, FIG. 6 is a bottom view of the zipper pull design of FIG. 1.
